UNITED STATES PATENT OFFICE.

THOMAS SPENCER MILLER, OF SOUTH ORANGE, AND JOSEPH H. DICKINSON, OF MONTCLAIR,
NEW JERSEY.

HOISTING AND CONVEYING DEVICE.

No. 879,113.

Specification of Letters Patent.

Patented Feb. 11, 1908.

Original application filed June 12, 1902, Serial No. 111,331. Divided and this application filed November 28, 1906. Serial No. 345,533.

To all whom it may concern:

Be it known that we, THOMAS SPENCER MILLER and JOSEPH H. DICKINSON, both citizens of the United States, and residents 5 of South Orange, county of Essex, and State of New Jersey, and Montclair, county of Essex, and State of New Jersey, respectively, have invented a new and Improved Hoisting and Conveying Device, of which the following is a specification.

The present invention relates to improvements in hoisting and conveying devices and this application is a division of our application for hoisting and conveying devices, filed 15 June 12th, 1902, Serial Number 111,331. In the accompanying drawings the invention is shown embodied in a cableway for collecting logs.

The invention consists of the construction, 20 combination and arrangement of parts set forth in and falling within scope of the appended claims.

In the annexed drawings Figure 1 shows in elevation a cableway embodying our invention. Fig. 2 is a plan view of the operating parts of the carriage such as is shown in Fig. 1. Fig. 3 is a detail partly in section, showing the construction suitable for the friction hoisting drum and the friction slack 30 pulling drum.

As has been stated in our application No. 111,331 above referred to, difficulty has been experienced in the operation of hoisting and conveying devices with cable carriage and load carriage, such difficulty to some extent 35 consisting in causing the fall, when unloaded, to promptly take up the slack in the lowering or fall rope. In the present invention, as in the application above mentioned, we have 40 provided a slack puller or means for paying out the hoist rope so that a prompt and rapid paying out of this rope may be secured.

Referring to the drawings in detail S and S' represent, respectively, head and tail 45 supports for a cableway, A the trackway cable, H the hoist or fall rope, and T the traction or carriage hauling rope. The head and tail supports are provided with suitable guides for the various ropes. Three friction 50 rope drums D, D', D'', are shown driven by a suitable engine; D having the traction rope connected therewith; D' and D'' having the rope or ropes connected therewith by which the raising or lowering of the load and the

fall rope is secured. Each of these friction drums may be, if desired, of the construction shown in Fig. 3, wherein the driven spur-wheel 1 fast upon the shaft 2 carries a V-shaped friction ring 3 entering a corresponding recess in the flange 4 of the rope drum 5 60 5 which is loose upon the shaft 2 and is pressed toward the spur-wheel 1 in opposition to the coil-spring 6 by the cross-key 7. A band brake 8 is applied to the exterior of the flange 4. When neither the band brake nor 65 the friction ring engages the rope drum it pays out its rope freely. When the band brake is disengaged but the friction ring is engaged, it hauls in its rope. When the friction ring is disengaged and the band 70 brake is engaged, it holds its rope stationary. When the brake is lightly engaged, the paying out of the rope is under tension. When the friction ring is so lightly engaged as to slip upon the flange 4 it acts as a yielding 75 take-up rope to instantly take in any slack that may occur in the rope which it controls. By utilizing these capabilities of the three friction rope-drums D, D', and D'', the operator at the engine is enabled to operate and 80 control the three ropes B', C', and T in the manner hereinafter described without permitting any substantially undesirable slack in any of said ropes.

Upon the trackway cable is a trolley F 85 from which is suspended a load carriage E containing the drum I, which receives the hoist or fall rope H, and the drum or drums which receive the hoist operating rope or ropes. Preferably the connection between 90 the load carriage E and trolley F is by links or other device which has a certain measure of flexibility sufficient to permit relative turning and bending between the two parts.

The carriage construction shown in the 95 drawings, and especially in Fig. 2 comprises a suitable frame having journaled therein a drum I for the fall or hoist rope and a drum G'' which receives the loop of a single rope composed of the two runs B', C', which communicates its motion to the drum by its frictional grip thereon. The fall rope drum I is a storage drum of sufficient capacity to accommodate the maximum length of fall rope which will be needed. The drum G'' 100 preferably contains an elliptical groove with sufficient wraps of the rope therein to give the rope a sufficient grip on the wheel;

though other gripping means may be substituted.

It is evident that by operating the hoist operating rope B', C', the fall rope may be raised or lowered at will and the speed of lowering is independent of the weight of that part of the rope then paid out, or the attachments thereto. It will therefore be possible to lower it at a greater rate of speed than where its weight alone is relied upon. The use of fall rope carriers may also be obviated with all the difficulties attendant thereto.

In moving the carriage along the trackway the hoist operating rope or ropes must be wound in or paid out to correspond with the movement of the carriage if there is to be any hoisting or lowering of the load. The two drums D' and D² are therefore required to operate this rope. The frame E is supplied with different points of attachment for the suspending links f, by means of small holes e, so that the suspension point may be shifted as necessary to make the ropes pull right.

In the construction of this device we employ two distinct friction-rope drums D', D², for operating the slack-pulling and hoisting ropes, respectively, so that by inhauling both of said drums in unison the drum mechanism on the load carriage may be held stationary as the carriage moves toward the head support and vice-versa, by paying out on the drums D', D² in unison, the drum mechanism on the load carriage may be held stationary as the load-carriage travels toward the tail-support. But when it is desired to operate the drum mechanism on the load carriage in either direction, it may be done by hauling in on one of the drums D' or D² while the slipping of the friction of the other drum permits it to pay out under sufficient tension to maintain any required tautness of said hoisting and slack-pulling ropes.

Although the carriage upon which the traveling drums are mounted is shown as traveling upon an elevated cable or track-way, we do not limit ourselves thereto since certain of the principles of our invention might be embodied in apparatus with the

traveling drums mounted upon other forms of conveyance.

50

What we claim is:

1. In a hoist conveyer, a track, a trolley on said track, a wheel carried by said trolley, hoisting mechanism actuated by said wheel, a cable passing over said wheel, independent winding drums receiving the ends of said cable, and a separate back-haul cable connected to said trolley, substantially as described. 55

2. In a hoist conveyer, a track, a trolley on said track, a wheel carried by said trolley, hoisting mechanism geared with said wheel, a cable passing over said wheel, independent winding drums receiving the ends of said cable, and a separate back-haul cable connected to said trolley, substantially as described. 60

3. In a hoisting and conveying device the combination with a trackway, a carriage thereon, means for traversing the carriage, a fall rope drum upon said carriage, and a fall rope upon said drum, of a hoist-operating 70 drum upon the carriage, gear driving connections between the two drums, two distant stationary drums, and a rope extending from one of the distant drums to and about the hoist-operating drum and then back in the 75 direction from which it came to the other distant drum, and means for turning said distant drums at the same or different rates of speed.

4. In a conveying apparatus, in combination, a trackway, a load carriage, a traction rope, a drum for operating the same, a hoist on the load carriage, a rope-drum-engine containing a hoisting-drum and a separate slack-pulling-drum, and a rope extending 85 from one of said drums to and wrapped around a member of said hoist and back again to the other of said drums.

In testimony whereof we have signed our names to this specification in the presence of 90 two subscribing witnesses.

THOMAS SPENCER MILLER.
JOSEPH H. DICKINSON.
